(54) PANACEA

(76) Inventor: **Jacob Houck**

Jacob Hornek

The Schedule referred to in these Letters Patent, and making part of the same, containing a description on the words of the said Jacob Hornek himself of his improvement in Medicine, called "Hornek's Panacea".

Be it known that I, Jacob Hornek of Baltimore in the County of Baltimore, in State of Maryland, have made a discovery in Medicine called "Hornek's Panacea" the mode of preparing which is described as follows.

(Take 25 gallons of Rye Whiskey: to which add 25^{lb} of Burnt Gum, 150^{lb} of sugar, 1^{lb} of oil of Juniper, & 5 oz. of oil of Lemon: incorporate these well together: then bottle the mixture & it will be fit for use. —)

Directions for using the Panacea.

Take the bottle two or three times: — then for an Adult take one table spoon full of the mixture before break fast; & two table spoons full at 11 o'clock & two table spoons full on going to bed. For children the doses may be regulated according to their ages. The doses may be increased or diminished agreeably to the feelings & constitution. In a few days after taking the medicine, you will be able to discover how it will act on the disease: & you can judge whether you should increase or diminish the doses. Should benefit arise from taking one or two bottles of the medicine, it should be continued until cured.

When the case is obstinate, it requires from three to five bottles to effect a cure: & after having discontinued the medicine for about two weeks, & every symptom of the disease has disappeared, then one or two bottles may be required to be given, especially where the disease has been obstinate & of long standing, that a certainty of a perfect cure may be obtained in the cure of the disease.

completely eradicated.

This medicine is an effectual cure for the following diseases. Hypopxia, loss of appetite, Indigestion, Inflammation of the stomach, Heart burn, Diarrhea, Dysentery or Flux, Cholera Morbus, Consumption, Influenza, colds, coughs, Inflammation of the chest, Palsey, Bout, Rheumatism, Inflammatory sore throat or Quinsy, Whooping cough, Thrush or sores mouth, Purulent sore throat, hoarseness, Inflammation of the heart, Dosey, Rickets, diseases of the liver, Jaundice, obstructed or painful menstruation, Difficulty of making urine, Blot, Thystenes, Measles & various affections of the members, & ligaments, Rheumatism & Venereal Diseases, ulcers, sores, affections of the skin or all diseases arising from impure blood &c.
